UNITED STATES PATENT OFFICE.

AUSTIN F. STOCKWELL, OF ARLINGTON, CALIFORNIA.

RAILWAY-ROAD-BED CONSTRUCTION.

1,223,140.

Specification of Letters Patent. Patented July 10, 1917.

Application filed January 27, 1917. Serial No. 144,858.

To all whom it may concern:

Be it known that I, AUSTIN F. STOCKWELL, a citizen of the United States, residing at Arlington Sta., in the county of Riverside and State of California, have invented certain new and useful Improvements in Railway-Road-Bed Constructions; and I do hereby declare the following to be a full, clear, and exact description of the invention, such as will enable others skilled in the art to which it appertains to make and use the same.

This invention relates to railway road bed construction, and has for its object the provision of a road bed that will take the place of the ordinary wooden ties now in use, the said road bed being formed of metallic sections that can be assembled into road bed formation, or removed therefrom, in a convenient and expeditious manner.

Another object of the invention is the provision of a road bed of this nature that will be of simple and durable construction, cheap to manufacture, will be efficient in operation, and has associated therewith novel types of rail fastening elements which will effectively clamp the rails of a track against spreading.

Other objects will appear and be better understood from that embodiment of my invention of which the following is a specification, reference being had to the accompanying drawing forming a part thereof, in which:

35. Figure 1 is a plan view of the meeting ends of two of the sections of the road bed,

Fig. 2 is a detail side view of one of the sections,

Fig. 3 is a transverse section on the line 40 3—3 of Fig. 1,

Fig. 4 is a perspective view of one of the rail-securing plates detached from operative position, and

Fig. 5 is a top plan view of the type of plate employed for each rail of a curved track, the curvature of the plate being shown greatly exaggerated.

Referring to the drawing in detail, where in the meeting ends of two of the sections of the road bed are shown, each section consists of a rectangular shaped base 1, formed of metal which extends throughout the length of the section. Extending transversely across the upper surface of the base

1 are a plurality of rectangular shaped metallic plates 2, which are arranged in spaced parallelism and have their opposite terminals bent downwardly to provide flanges 3, which engage the opposite longitudinal edges of the base 1. A pair of companion rail sections 4 rest upon the upper sides of the plates 2, and each plate is provided, adjacent its opposite ends, with upstruck portions which are bent into angular formation to provide rail clamping elements 5 which engage over the outer longitudinal edges of the base flanges of the rail sections 4, as shown more particularly in Fig. 3 of the drawing. Detachable rail-clamping elements 6 are located inwardly of the rail sections 4 and each consists of an elongated plate 6 which rests upon the upper side of the adjacent plate 2, and has its outer end bent to provide a rail-engaging flange, as shown in Fig. 3, and which flange engages over the adjacent inner longitudinal edge of the adjacent rail 4. The opposite end of the plate 6 is bent downwardly, as shown at 7, and extended through an opening 8 in the plate 2 and terminally engaged in a recess in the base 1, as shown in Fig. 3 of the drawing. Fastening elements 9 extend through openings in the plate 6 and through openings 10 in the plate 2 and engage in openings in the metallic base 1, so as to prevent accidental upward movement of the plate 6 when in operative position.

The component parts forming each individual section of the road bed are so constructed that they can be conveniently assembled into unit formation, after which the completed unit or section is placed in operative position and lined up with adjacent units or sections so as to complete the road bed.

In Fig. 5 there is shown the type of plate adapted to be employed for each rail of a curved track, the said plate being shown in the shape of a sector, so as to admit of a plurality of such plates being arranged in close relation.

The plates 2 when in operative position are arranged in spaced relation, as shown more particularly in Fig. 1, so as to admit of the contraction and expansion of the plates.

It is evident that various changes might be resorted to in the construction, form and

arrangement of the several parts without departing from the spirit and scope of the invention as claimed.

Having thus described my invention what I claim as new, is:

1. In railway road bed construction, a plurality of detachable sections, each section consisting of a base, a plurality of spaced plates mounted on the upper side of the 10 base, flanges formed on the plates and engaging the opposite side edges of the base, and rail fastening elements carried by the plates.

2. In railway road bed construction, a 15 plurality of sections, each section consisting of a base, a plurality of spaced plates extending transversely across the upper side of the base, each of the plates being provided adjacent its opposite ends with up- 20 struck portions formed to provide rail-

clamping elements adapted to engage the outer longitudinal edges of the companion rails of a track, and rail-engaging elements detachably associated with the plates for engaging the inner sides of the base flanges 25 of the rails of a track.

3. In railway road bed construction, a plurality of detachable sections, each section consisting of a base, a plurality of spaced plates extending transversely across the upper side of the base, and rail fastening elements formed integral with the plates adapted to engage the outer sides of the base flanges of the companion rails of a track.

In testimony whereof I affix my signature 35 in presence of two witnesses.

AUSTIN F. STOCKWELL.
